SPACE THERMOSTAT

William D. Gibson, Portland, Oreg., assignor to Iron
Fireman Manufacturing Company, Portland, Oreg.

Filed July 5, 1960, Ser. No. 61,214

Term of patent 14 years

(Cl. D52—7)

FIG. 3.

FIG. 1.

FIG. 2.

Fig. 1 is a view in front elevation of a space thermostat, showing my new design.

Fig. 2 is a view in side elevation of the thermostat of Fig. 1.

Fig. 3 is a view in top plan of the thermostat of Fig. 1. The undisclosed side of the thermostat is substantially plain in appearance.

I claim:

The ornamental design for a space thermostat, as shown and described.
